GUIDING DEVICE FOR CURTAIN
DRAW-CORDS

Max Sadineff and Abe Holtz, New York, N. Y.

Application July 26, 1951, Serial No. 238,692

5 Claims. (Cl. 160—344)

1

This invention relates to guides for the draw-cords for curtains, and has particular reference to a guiding device which is detachably and easily fitted to a curtain rod and which will smoothly and easily guide the draw-cords to enable the same to effectively cause closing and opening movements of the curtain.

An object of the invention is to provide a guiding device of this character which can be very easily fabricated from metal or other suitable material; which can be readily affixed in position on a curtain rod, and which will properly guide the draw-cords to permit a smooth operation of the same and the curtains controlled thereby.

More particularly, the invention contemplates the provision of a guiding device, especially adapted for use in connection with curtain rods of the channel type and wherein the guiding device fits within the channel and is provided with projecting arms or tongues formed with apertures through which the draw cords are guided.

These and other objects are attained by the invention, a more particular description of which will hereafter appear and be set forth in the claims appended hereto.

In the accompanying drawing, wherein several illustrative embodiments of the invention are disclosed,

Fig. 1 is a front elevational view of a curtain rod, with a curtain thereon and provided with the improved draw-cord guiding means;

Fig. 2 is a perspective view of one of the guiding devices;

Fig. 3 is a perspective view of a modified construction;

Fig. 4 is a perspective view of one end of a curtain rod, showing a portion of a curtain thereon and with a part thereof broken away, and also showing how the draw-cords extend through the guiding apertures in one of the guide members fitted to the rod;

Fig. 5 is a sectional view taken on the line 5—5 of Fig. 4, looking in the direction of the arrows;

Fig. 6 is a sectional view taken on the line 6—6 of Fig. 5, looking in the direction of the arrows; and

Fig. 7 is a modified construction which can be made from a single piece of wire.

Referring to the drawings, and particularly to the embodiment of the invention shown in Figs. 2, 4, 5 and 6, a curtain rod of known construction is disclosed at 10. The same is of the flat type, usually formed of sheet metal or of plastic material and of channel or C-shape in cross section. The channel in the rod is indicated at 11. At its 55

2

opposite ends, the rod 10 is bent laterally as shown at 12, which ends 12 are formed with holes 13 through which supporting hooks 14 secured to the window-frame, are inserted to hold the rod above the window before which the curtains are suspended.

In each of these off-set or laterally-bent ends 12 is provided a draw-cord guide member, indicated at 15 and shown most clearly in Fig. 2. Each of these guide members is provided with a relatively wide plate portion 16 of a width which enables it to snugly fit within the channel 11 of the rod in the lateral end portion 12. If necessary, the side flanges 18, 19 of the rod may be crimped or slightly bent to grip the plate portion 16 or otherwise engage it to hold the guide member stationary in the end portion 12 of the rod. However, a tight fit of the guide member in the channel of the rod is not strictly essential since the guide member is confined in the lateral end of the rod as will be explained.

Extending from one end of the plate portion 16 is an arm 20 which is curved laterally and provided at its end with an enlargement 21 provided with two apertures 22 which may be surrounded by eyelets or other annuli providing guide openings through which draw-cords 23 may slide smoothly and easily. The arm 22 constitutes the rear arm of the guiding device, and at the opposite edge of the plate portion 16 is formed a longer arm 24 which is also curved and is provided at its free end with an enlarged portion 25 provided with two eyeleted apertures 26.

In Figs. 1, 4 and 5 is shown the manner in which the guide members appear when fitted in position at the opposite ends of the curtain rod and how the draw cords 23 are extended through the apertures 26 and 22 of said guide members. It will be therein noted that the enlarged end portions 21 and 25 of the guide members are disposed on the outside of the channel 11 and at the back of the rod. The curtain sections 27 and 28 are drawn apart by the draw-cords 23 in the known manner, and said cords extend through the channel 11 of the rod and pass through the apertures 26 and 22 to depend downwardly in the usual free ends for manipulation of the curtains. By pulling on one or the other of the dependent ends of the draw-cords 23, the cords will be drawn smoothly and easily through the guide members to effect closing or opening operations of the curtains. When the guide members are fitted in position in the ends of the curtain rod, they can be readily maintained in such ends by being confined between the hooks 14 and the bend 40 in the rod.

The guide members 15 may be easily fabricated from a single strip of sheet metal, or formed of plastic if desired. These guide members enable the draw-cords to smoothly slide through their eyeletted apertures and the use of pulleys or rollers usually employed in draw-curtain constructions is thus obviated.

In the embodiment of the invention shown in Fig. 3, a plate member 30 is provided at one end of a strip 31, said plate member 30 constituting the base or anchoring plate for the guide member, and being thus similar in function to that shown at 16. A long curved arm 32 extends from one edge of the plate member 30, said arm being provided with a widened portion 33 substantially close to the plate member 30. Eyeletted guide apertures 34 are provided in the plate 33. At the free end of the long arm 32 is formed an enlargement 35 which is angularly disposed and is formed with the eyeletted apertures 36. In this embodiment of the invention, the greater portion of the arm 32 including the enlargements 33 and 35 is located out of the channel 11 and thus disposed on the inner side of the curtain rod, and the draw-cords are extended through the apertures 36 and 34 and the curtain operated in the manner explained in conjunction with the first embodiment of the invention.

The two embodiments of the invention thus far described suggest that the guiding device be made from flat stock or possibly made from strip material. In the embodiment shown in Fig. 7, the guiding device is shown as being formed from a single piece of springy wire. This device is formed with the two springy leg portions 41 and 42 which normally tend to spring apart slightly to thus frictionally engage the interior of the channel of the curtain rod. The leg 41 is provided at one end with the guide loop 43, corresponding to one of the apertures 22 and 34, while the end of the leg 42 is provided with a guide loop 44 corresponding to the second guiding aperture 22 and 34. At their opposite ends the legs 41 and 42 are integrally joined in a double loop or figure-8 formation to thus provide the two loops 45 and 46 corresponding in function to the guiding apertures 26 and 36.

The several guiding devices herein described are such as can be inexpensively constructed and applied to curtain rods of known construction, thus converting such rods from supports for immovable curtains to rods which enable draw curtains to be employed upon them.

Having described several embodiments of the invention, it is obvious that the same is not to be restricted thereto, but is broad enough to cover all structures coming within the scope of the annexed claims.

What we claim is:

1. A guiding device for curtain draw-cords and for application to a curtain rod of the channel type, said guiding device composed of a length of springy wire having two springy leg portions adapted to be fitted in the channel of the rod, each of said leg portions being provided at one end with a cord-guiding loop, the two legs being

integrally connected at their opposite ends into a double loop providing two cord-guiding loops, the double loop and the loops at the opposite ends of the legs being located outside of the channel in the rod.

2. A guiding device for curtain draw-cords and for application to a curtain rod of the channel type, said guiding device consisting of a single elongated strip member having a widened plate portion closely fitting within the channel of the curtain rod and confined in said channel, a single curved arm integrally formed on and projecting from said wide plate portion and being partly disposed outside of the channel and located at the back of the curtain rod, said curved arm being provided with a pair of enlargements also located on the outside of the rod, each of said enlargements being provided with a plurality of cord-guiding apertures.

20 3. A guiding device for curtain draw-cords and for application to a curtain rod of the channel type, said guiding device consisting of a single, elongated strip member having a widened plate portion at each end, said plate portions being connected by a narrower strip, the greater portion of said strip being disposed in the channel of the rod, the enlargements at the ends of said strip being disposed externally of the rod and at the back of the same and having apertures through which a pull-cord is disposed, and a plate portion of a width fitting within the channel of the rod located on the strip between the enlargements thereof and fitted within the channel of the rod.

25 4. A guiding device for curtain draw-cords and for application to a curtain rod of the channel type, said guiding device consisting of a single flat strip having an enlarged head at one end fitting within the channel of the rod and confined therein, the remainder of the strip being disposed on the outside of the channel and at the back of the rod, said exposed portion of the strip being provided with a pair of enlargements having apertures for curtain draw-cords, one of said enlargements being located at the free end of the strip.

30 45 5. A guiding device for curtain draw-cords and adapted for application to a curtain rod of the channel type, a guiding device consisting of a member having an enlarged part fitting within the channel of the rod and confined therein, arm portions at the opposite ends of the enlarged part extending out of the channel, said arm portions being provided at their outer ends with apertures for the reception of draw-cords.
